LOADING BLADE DISPENSERS

Robert L. Sinclair, Dedham, Mass., assignor to The Gillette Company, Boston, Mass., a corporation of Delaware

Original application January 8, 1953, Serial No. 330,214, now Patent No. 2,722,308, dated November 1, 1955. Divided and this application March 28, 1955, Serial No. 497,211

9 Claims. (Cl. 53—37)

This invention comprises a novel process of loading dispensers with thin sharp-edged blades such as safety razor blades.

The present application is a division of my application Serial No. 330,214 filed January 8, 1953, now issued as U. S. Patent No. 2,722,308 on November 1, 1955.

The invention is herein shown in its application to a dispenser constructed at least in part of resinous plastic material that may be readily and accurately molded to shape. Such plastic materials have the advantage of being light in weight, moisture and corrosion proof and of low cost to the manufacturer. They are, however, under some conditions subject to deformation by cold flow of the plastic material when subjected to continuous stress, as for example, the pressure exerted by a spring located within the dispenser for positioning the blade stack. An object of the present invention is to obviate this weakness by providing in the dispenser a self-contained metallic system effective to exert continuous pressure upon the blade stack independently of the plastic elements of the dispenser.

In the illustrative example herein shown, the main body of the dispenser may be molded from resinous plastic, and this combined with a sheet metal cover which is connected to the plastic body and provided with a thumb or finger opening. A bowed spring is disposed within the dispenser and supported entirely upon the metal cover independently of the plastic body and of the connection between the plastic body and the metal cover. The bowed spring is supported in such a position as to bias the blade stack always toward the finger opening of the cover, and in this manner a completely self-contained metallic system including the spring is provided. The plastic body is, therefore, entirely relieved of continuous stress so that it may be relied upon to hold its shape for an indefinite period of time and is not subject to deformation regardless of changes in temperature that it may undergo.

The process of the invention is characterized by the steps of superimposing a stack of blades upon a flat spring plate or blade, then curving or bowing the plate in situ, and finally latching or fastening the plate in its bowed and stressed condition while maintaining the blade stack undisturbed above it.

Preferably and as herein shown, the metal cover is flanged to support the opposite edges of the spring plate and under these circumstances, this plate may be bowed by pressure exerted on it through the superposed blades of the stack and brought into its flange-supported position while in bowed condition, all without imposing any stress upon the plastic body of the dispenser.

Going more into detail, it is proposed to assemble the blades in stack formation upon a flat spring plate within the dispenser, then to bow the spring transversely by pressure exerted in part through the blade stack, and finally, to transfer the spring-supporting function to flanges of the cover, thereby biasing the blade stack toward the

2

finger-opening of the cover while leaving the plastic body of the dispenser entirely free of stress.

The dispenser has further novel features of construction, and among them are those that provide within the body of the dispenser a used blade compartment. This is effected, as herein shown, by forming at both ends of the plastic body tables or platforms raised above the bottom and shaped to locate a blade-supporting plate at a level suitable for the top of an underlying chamber. Blade inlet slots are provided in the bottom of the base at the inner end of each table. The tables not only locate the blade-supporting plate for this purpose, but also supply rests for it during the blade loading operation, although it may be temporarily lifted from the tables while the spring is being bowed in engaging it with the flanges of the sheet metal cover. A characteristic and desirable feature of the dispenser is that it employs a normally flat spring and that the maximum deformation of the spring is initially imparted to it by the steps of the process herein disclosed. As the spring performs its function of progressively moving the uppermost blade of the stack into discharging position, the deformation and stress of the spring gradually decreases; that is to say, the spring approaches its normal flat condition progressively as the number of blades in the stack approaches exhaustion.

These and other features of the invention will be best understood and appreciated from the following description of a preferred embodiment thereof selected for purposes of illustration and shown in the accompanying drawings in which:

Fig. 1 is a view in perspective of the elements of the dispenser shown in exploded relation.

Figs. 2 and 3 are views in cross section, partly in elevation, illustrating the loading and assembling steps.

Fig. 4 is a view in perspective of the loaded dispenser, and

Fig. 5 is a bottom view of the same.

In its illustrated form the dispenser comprises four elements in addition to the blade stack which it contains. These, as shown individually in Fig. 1, comprise a body molded of plastic resin, a metal spring plate which is initially flat, a ribbed supporting plate of sheet metal and a cover, also of sheet metal.

The plastic body, while not necessarily of uniform thickness in all its parts, is designed so that its mass is distributed as equally as possible throughout its entire area, since this is a condition facilitating both the molding operation and the sturdiness of the molded structure. The body comprises a flat bottom 10 substantially rectangular in contour and having upright side walls 11 and 12, both of which are interrupted so as to form a wide notch or recess symmetrically located in the walls on opposite sides of the body. The lower edges of the wall sections are provided with a downwardly opening channel 13 for the reception of flanges on the side wall of the cover as will presently appear. The bottom 10 terminates at each end in a semicircular recess or opening 14 while the side walls 11 and 12 extend beyond these recesses and are connected by low end walls 15 and 16. From the end walls extend inwardly flat tables 17 and 18 with rounded inner ends, and from these tables extend upstanding studs 19 and 20. The tables 17 and 18 are located substantially above the level of the bottom 10 and serve initially to hold the supporting plate which underlies the blade stack.

Each end wall 15 and 16 merges into an upwardly curved bottom section shaped to supply at one end the lower edge 21 of a blade exit opening and at the other end to provide a lower edge 22 for a corresponding exit opening. These bottom sections extend between the side walls 11 and 12 and are provided at each end with a

projecting cover-supporting lug 23—24 which is located slightly below the top edge of the side walls. Both of the side walls are provided at each of their ends with external pads 25 which provide shoulders against the inner edges of which the ends of the cover are to be fitted and which also supply a pleasing finish to the dispenser as a whole.

The bottom 10 is also provided with a pair of spaced parallel apertures in the form of slots 26 located symmetrically in the median transverse axis of the bottom 10 and serving to admit the passage of spring flexing blades or tools as will be presently described.

The spring leaf or plate 30 as shown in Fig. 1 is rectangular in shape and provided with rectangular ears 31 in its front and rear edges. In assembling the dispenser, the leaf 30 is placed in a flat position upon the bottom 10, being of the width to fit with clearance in the recesses formed by the interruption of the side walls 11 and 12. The ears 31 are spaced to gauge the spring plate transversely and locate it symmetrically with respect to the bottom 10 by engaging the upstanding side walls of the base. As shown in Fig. 1, the spring leaf 30 is initially and normally flat. It is, however, bowed transversely in assembling the elements of the dispenser and remains in upwardly concave position in the loaded dispenser.

The supporting plate is rectangular in outline and comprises a flat central portion 35 connected by two downwardly converging ribs 36 to flat parallel side portions which lie in the same plane as the central portion 35. This portion is provided with long slots 37 at both ends shaped to receive with clearance the upstanding studs 19 and 20 of the base. The ribs 36 are cut away at both ends so that the notched ends of the central portion 35 may rest flatly upon the tables 17 and 18 of the base and are reduced in depth throughout their central sections for a distance corresponding to the length of the recesses of the side walls 11 and 12. The side sections of the supporting plate are provided with elongated notches or recesses 38 to afford clearance for the ends of the spring plate 30, when the latter is subsequently bowed upwardly at its outer edges about the ribs 36 as fulcrums. A function of the plate 35 is to support the blade stack always in flat condition. This is important when only 2 or 3 blades remain in the stack as if the spring bore directly on them, it would cause bowing that might interfere with proper discharge of the blades. The plate keeps even the last blade of the stack in flat condition.

The cover 42 is formed from a single integral blank of spring sheet metal and includes a flat rectangular portion provided symmetrically with an elongated thumb or finger opening having an inturned rim 43, and is folded inwardly at both ends to provide rounded edges 44 and 45 cooperating with the edges 21 and 22 to provide the upper edges of blade exit openings at opposite ends of the dispenser.

The cover is also provided with down-turned side walls 46 and 47 which correspond in length to the distance between the pads 25 of the base and are provided at the lower edges with up-turned flanges 48, 49 designed to fit in the channels 13 already mentioned as being provided in the lower edges of the walls 11 and 12. The down-turned side walls 46 and 47 are located symmetrically in the cover and the up-turned flanges 48 and 49, as will be apparent from Fig. 1, have shallow end portions and central portions 50 and 51, respectively, of substantial height. The high portions 50 and 51 of the up-turned flanges are symmetrically located in the transverse median axis of the cover and correspond in length approximately to the width of the spring plate 30 and the recesses formed in the side walls of the base. They are biased inwardly to positions beneath the outer edges of the spring leaf 30 as indicated in Fig. 3.

The dispenser is herein shown as designed to contain 12 to 20 unwrapped safety razor blades 40 of the type shown in Fig. 1, that is to say, doubled-edged longitudinally slotted blades having corner notches defining

elongated unsharpened end portions. The blades are arranged in the dispenser alternately in longitudinal overlapping relation. The slots on one series of the blades are engaged by the abrupt outer shoulder or end edge of the stud 20 while the slots of the other series are correspondingly engaged by the shoulder or outer edge of the studs 19. Each blade, therefore, is positively held against inward movement but may be readily displaced and ejected by outward movement under traction supplied by the thumb of the user and removed through its adjacent exit opening. While the blade stack rests upon the plate 35 it will be seen that the studs 19, 20 pass through the end notches of the plate and enter the slots of the blades upon the plate.

It will be seen that (1) the recesses provided in the opposite sides walls of the plastic base, (2) the elongated notches 38 in the opposite edges of the blade-supporting plate, (3) the sections of reduced depth in ribs 36, and (4) the spring 30 are all of the same longitudinal dimension and are all located in transverse registered positions when assembled in the dispenser.

The loading and assembling steps are carried out to best advantage with the assistance of a fixture like that shown in Figs. 2 and 3. This comprises a base 60 containing a movable bed-plate 61 supported in an initial elevated position by spring-encircled studs 62 guided for vertical movement in bushings provided in the base 60. The side walls of the base are flanged to limit the upward movement of the bed-plate 61 and hold it at a pre-determined level. A pair of spaced upstanding spring-flexing pins 63 project upwardly through holes in the bed-plate 61, and these pins are designed to pass freely through the holes 26, already described as provided in the bottom 10 of the plastic base of the dispenser.

The fixture also includes a vertically movable plunger 70 of such dimensions as to pass freely through the finger opening 43 of the sheet metal cover. The plunger is provided with the shoulder 71 and is surrounded by a sleeve 72, which is initially engaged by the shoulder 71 and provided with vacuum passages 73 terminating in ports located in the end of the sleeves. The sleeve 72 is thus adapted to pick up the sheet metal cover 42 and to move it forcibly downward in registration with the plastic base which has already been presented to the bed-plate 61 in the position shown in Fig. 2.

The plastic base is positioned upon the bed-plate 61 with the blade-supporting plate 35 resting upon the raised tables 17, 18 and with a stack of blades 40 positioned thereon by the studs 19 and 20 which pass upwardly through the end notches 37 of the ribbed plate. The elements above-described are shown in this position in Fig. 2.

In the actual assembling step the plunger 70 is first brought into contact with the blade stack and then the sleeve 72 descends with the sheet metal cover 42. Then both the plunger and the sleeve descend together, depressing the bed-plate 61 and causing the pins 63 to engage the spring leaf 30 which until now has lain in flat condition upon the bottom 10 of the base with its side edges extending into the recesses in the side walls 11 and 12. As this movement continues, the spring 30 is bowed upwardly at both edges to a position of maximum deformation over the ribs 36 of the blade-supporting plate which now acts as fulcrums. Meanwhile, the side walls 46 and 47 of the sheet metal cover encounter the upwardly tapering sections of the walls 11 and 12 of the base and are deflected outwardly by camming action with the result that the opposite edges of the bowed spring pass upwardly above the edges of the upstanding flanges 50 and 51, while these flanges move inwardly beneath the edges of the spring as soon as the side walls 46 and 47 have passed downwardly beneath the wall sections 11 and 12 so that they can snap into the channels 13 in the base of these walls. The elements are shown in this position in Fig. 3, and it will be apparent that when the parts of the fixture are now separated, the spring 30 will be left in bowed

condition biasing the spring-supporting plate 35 upwardly and yieldingly holding the uppermost blade in the stack against the downturned rim 43 of the finger-opening and always in flat condition so that it may be properly discharged through the exit slot.

The side walls 46 and 47 of the cover have meanwhile filled the space between the end pads 25 of the side walls 11 and 12 of the base, and the shallow upturned flanges of these walls have snapped into the channels 13 thus permanently uniting the cover and base. The stack of blades 40 is enclosed within the dispenser and the spring 30 is mounted in bowed condition upon the upstanding flanges of the metal cover. The upward thrust of the spring is, therefore, carried entirely in a closed metallic system and the plastic base relieved of all continuing stress. While the spring is herein shown as an initially flat leaf, any other form of spring may be employed with corresponding modification of its metal supporting structure.

Having thus disclosed my invention and described in detail an illustrative embodiment thereof, I claim as new and desire to secure by Letters Patent:

1. The process of loading dispensers with thin flexible safety razor blades, which is characterized by the steps of superimposing a stack of sharp-edged blades upon a flat spring within the dispenser, then curving and stressing the said spring in situ beneath the blade stack, and latching the spring in its curved and stressed condition while maintaining the blade stack undisturbed above it.

2. The process of loading dispensers with thin flexible blades, which is characterized by the steps of assembling thin, sharp-edged blades in stack formation above a flat spring and within a dispenser, bowing and stressing the spring transversely beneath the blades while maintaining the arrangement of the blade stack undisturbed, and then locking the opposite edges of the bowed spring in position to maintain the spring permanently under stress beneath the blade stack.

3. The process of loading with thin flexible blades a dispenser which has a plastic body and a flanged sheet metal cover, which is characterized by the steps of assembling a stack of thin, sharp-edged blades above a flat spring within the body of the dispenser, then supporting the opposite edges of the spring and bowing and simultaneously stressing the spring beneath the blades by pressure exerted on the superposed blades, and finally engaging the opposite edges of the bowed spring with the flanges of the cover.

4. The process of loading with thin, sharp-edged blades a dispenser having a plastic body and a flanged sheet metal cover perforated by a finger opening; the process comprising the steps of assembling a stack of the blades

upon a flat spring in the body of the dispenser, supporting the spring at its opposite edges, bowing and stressing the spring downwardly by pressure exerted through the blade stack, spreading the flanges of the cover, and finally transferring the spring-supporting function to the flanges of the cover, thereby pressing the blade stack toward the finger opening of the cover.

5. The process of loading with thin sharp upwrapped blades a dispenser having a plastic body and a flanged sheet metal cover, comprising the steps of assembling a stack of the blades within the plastic body of the dispenser while resting upon a flat spring, bowing and stressing the spring in situ beneath the blade stack, and then, without disturbing the stacked arrangement of the blades, forming a self-contained metallic system including the bowed spring and the metal cover.

6. The process of loading with thin, sharp-edged blades a dispenser having a plastic body with a flat bottom and a metal cover with upturned resilient flanges rising above the sides of the bottom, the process including the steps of supporting the flat bottom of the dispenser and said upturned flanges, resting a normally flat spring upon the supported bottom of the dispenser, locating a stack of blades above the spring, then spreading the flanges, forcibly bowing the spring between them by pressure exerted through the blade stack, and contracting the flanges into spring-supporting position beneath the bowed spring.

7. The process defined in claim 6 in which the spring is bowed by downward pressure exerted through the blade stack supplemented by upward pressure exerted on spaced areas of the spring by pins projected through holes in the bottom of the dispenser.

8. The process defined in claim 7 in which the resilient flanges of the cover snap under the edges of the bowed spring and maintain it in bowed condition thrusting against the blade stack.

9. The process of assembling and loading with razor blades a dispenser having a plastic bottom and a sheet metal top with side walls shaped to interlock with the bottom, comprising the steps of locating a stack of blades upon a flat spring on the bottom of the dispenser, and then bowing the edges of the spring upwardly beneath the stack and simultaneously both forcing the side walls of the top into interlocking engagement with the bottom and the bowed-up edges of the spring into engagement with the metal top forming a closed metal system which includes the spring.
